(57) CLAIM

The ornamental design for a smartphone wallet sleeve with clip and pop-up stand, as shown and described.

DESCRIPTION

FIG. 1 is a top front perspective view of the smartphone wallet sleeve with clip and pop-up stand, showing the pop-up stand in the retracted position;

FIG. 2 is a top front perspective view of the smartphone wallet sleeve with clip and pop-up stand, showing the pop-up stand in the extended position;

FIG. 3 is a bottom rear perspective view thereof, showing the wallet sleeve opening;

FIG. 4 is a bottom front perspective view thereof, showing the wallet sleeve opening;

FIG. 5 is a front view thereof;

FIG. 6 is a rear view thereof;

FIG. 7 is a left side view thereof, with the right side a mirror image of the left side;

FIG. 8 is a top view thereof;

FIG. 9 is a bottom view thereof;

FIG. 10 is a top front perspective view thereof shown in use with the pop-up stand in the retracted position; and,

FIG. 11 is a top front perspective view thereof shown in use with the pop-up stand in the extended position.

The broken lines depict environmental subject matter, are for illustration only, and form no part of the claimed design.
